MEANS FOR OBTAINING FLAME EFFECTS
IN NEGATIVE GLOW DEVICES

Andrew F. Henninger, Jr., Chicago, Ill.

Application May 18, 1931, Serial No. 538,052

7 Claims. (Cl. 176—14)

This invention relates to negative glow devices and has for its principal purpose the provision of a negative glow device wherein a flaming effect in conjunction with the figure design or 5 legend may be obtained.

My invention also contemplates the provision of novel means for controlling the discharge between electrodes in a negative glow device whereby to create a visible flaming appearance between 10 the electrodes.

My invention contemplates further the provision of a novel combination embodying a flaming discharge between electrodes and a flashing design. With this combination, it is possible to 15 obtain some very striking and attractive effects which may be used for display purposes.

I will describe the preferred form of my invention by reference to the accompanying drawing wherein—

20 Fig. 1 is a side view partly in section of the negative glow device embodying my invention;

Fig. 2 is a partial section on the line 2—2 of Fig. 1 combined with a circuit diagram illustrating the manner in which the electrodes are 25 operated;

Fig. 3 is a diagrammatic view of another method of providing the flaming effect; and

Fig. 4 is a diagrammatic view similar to claim 3.

30 Referring now in detail to the drawing, I find that, by using certain combinations of elements in a gas filled envelope, for example, one containing neon or other gas such as argon, krypton, helium, zenon, or mercury vapor, I can produce 35 a flaming discharge which when properly applied greatly enhances the striking effect produced by the negative glow in conjunction with an electrode having a particular design embodied therein. I find that to obtain the best results, it is necessary to use a practically pure gas because, if 40 impure gases are used, the flaming effect is reduced; if the impurities are too great, it is eliminated completely. I also find that, while a slight amount of impurities or other gas in the gas 45 bring out the figures or designs more distinctly, the brilliant glow due to the gas is destroyed to a certain degree particularly when neon gas is used as the filling.

50 In preparing the envelopes, I preferably use a slightly higher pressure than that I normally use in negative glow devices. With neon gas, the normal pressure I have used is about ten to twelve millimeters of mercury, and, for obtaining the 55 best flaming effect, I find it is better to use a

pressure of around eighteen to twenty millimeters of mercury.

Referring now to Figs. 3 and 4 as embodying the simplest form of the invention, I have two electrodes 5 and 6 which, if placed in a neon gas atmosphere in a properly prepared envelope, will glow when a gaseous discharge takes place therebetween due to a potential being impressed upon the leads 7 and 8. With such a structure embodying only the two electrodes however, I find that 10 I do not obtain the beautiful flaming effect, and, in order to insure obtaining the flaming effect, I preferably use a shield or barrier 9 which may be of the shape shown in Fig. 3 or that shown in Fig. 4. This barrier is preferably entirely disconnected from the exterior of the tube so far as any conductive connection is concerned. The shield may be made of metal which I have found to be very satisfactory or it may be made of some other suitable substance. The discharge when 20 initiated with the shield 9 in place follows the shortest path between electrodes 5 and 6, as for example in the direction of the arrows shown in Figs. 3 and 4, and along this path there is produced the appearance of a flame or moving glow. 25

As to the exact cause or theory underlying this phenomenon, I am not sufficiently sure to state such theory; however, I find that I am able to reproduce this condition at will by using a shield in the manner shown in the drawing and con- 30 forming to what is otherwise good practice in the art of making negative glow devices.

This flaming effect giving the appearance of burning designs on the electrodes 5 and 6 permits me to employ the effect in a number of 35 striking ways one of which is illustrated in Figs. 1 and 2. In these figures an evacuated bulb or envelope 10 has mounted therein a plurality of elements 11, 12, 13, and 14. Element 12 forms the shield and in the present instance has cut out 40 therefrom a design indicated by the word "Radio" at 15. Similarly electrode 14 has a certain design as indicated at 16 cut out from it.

The lead-in wires 17 and 18 and 19 serve also as the supporting means for supporting the elements, and the element 12 which has no lead in wire is supported by means of the insulated bushings, indicated for example at 20 and 21, from the elements 11 and 13.

The circuit connections are provided in Fig. 2 50 by means of which electrode 11 may always be kept in circuit while electrodes 13 and 14 are alternately caused to glow. The circuit disclosed in Fig. 2 is very simple and, of course, may be made more involved if it is desired to use a large 55

number of electrodes to obtain different effects. It consists essentially of the input transformer 21, limiting resistance 22, a thermostat 23 having a heating coil 24 and adapted to open and close one circuit at 25. Electrode 11 is connected as shown to one end of the transformer 21 while electrode 14 is connected to the other end of the transformer. Electrode 13 being closer to electrode 11 and slightly larger than electrode 14 will 10 tend to take the current when it is connected in parallel with electrode 14. It is, however, alternately connected in parallel and removed by means of the thermostat 23 and a heating coil 24. Since the details of this circuit have been explained fully in my previous applications, Serial No. 516,079 and Patent No. 1,960,245, dated May 29, 1934, it is believed that the operation thereof to alternately cause electrodes 13 and 14 to glow will be understood without further explanation.

When two of the electrodes are glowing, I obtain a very striking effect in that the front side of electrodes 11 which may be insulated on the back side as indicated at 26 will glow and the discharge will take place from say electrode 13 to electrode 11 and produce fiery streamers passing through the openings of the design 15 in the shield 12 because this is the shortest path to electrode 11. The effect, therefore, is that the top of electrode 13 is burning, and the flames are being sucked through the openings in the shield 12 to the glowing background or fire which is merely the negative glow on the surface of electrode 11. Electrode 14 being dark at this time also shows a glow through the design opening 16 to produce an added attraction. Now if the circuit is changed by the opening of contact 25 by thermostat 23, electrode 13 will become dull or dark while electrode 14 will glow, and the same fiery streamer effect from the top of 14 will continue to occur. Instead of having a glowing design or legend upon a dark background, there will now be present a glowing background with the dark letters.

By various combinations of this character, I am able to present some very striking and attractive displays.

From the above description, it is believed that the construction and operation of this device will be clear to those skilled in this art. It is also believed to be obvious that various minor modifications may be made without departing from the scope of the invention as set forth in the opening paragraphs of the specification and in the claims.

Having thus described my invention, what I claim as new and desire to secure by Letters Patent is:

1. A negative glow device comprising an envelope having a gaseous filling of the inert gas group at a pressure of above fifteen millimeters of mercury and having therein a pair of spaced electrodes associated to form a design, means for connecting a source of alternating current across said electrodes to cause negative glow on both, and a shield interposed in the path of discharge between said electrodes operating upon passage of current between said electrodes to cause a flaming light between the electrodes in addition to the glow on the electrodes the edges of said shield extending beyond the edges of at least one of said electrodes.

2. A negative glow display lamp structure for causing flaming effects between electrodes of the lamp including an envelope, a gaseous filling for said envelope at a pressure of approximately eighteen to twenty millimeters of mercury, a pair of display forming electrodes in said envelope, means for connecting a source of alternating current across said electrodes to cause negative glow on both, and a shield interposed between the electrodes, said shield having restricted passages therethrough.

3. A negative glow display lamp structure for causing flaming effects between electrodes of the lamp including an envelope, a gaseous filling for said envelope at a pressure of approximately eighteen to twenty millimeters of mercury, three display forming electrodes in said envelope, means for selectively and successively connecting a source of alternating current across different pairs of said electrodes whereby to cause negative glow on the pairs of electrodes, and a shield interposed between one pair of the electrodes.

4. A negative glow display lamp structure for causing flaming effects between electrodes of the lamp including an envelope, a gaseous filling for said envelope at a pressure of approximately eighteen to twenty millimeters of mercury, three display forming electrodes in said envelope, means for selectively and successively connecting a source of alternating current across different pairs of said electrodes whereby to cause negative glow on the pairs of electrodes, and a shield interposed between one pair of electrodes, said shield and one of said electrodes having openings therein in the form of display legends.

5. A negative glow display lamp structure for causing flaming effects between electrodes of the lamp including an envelope, a neon gas filling for said envelope at a pressure of approximately eighteen to twenty millimeters of mercury, three display forming electrodes in said envelope, means for selectively and successively connecting a source of alternating current across different pairs of said electrodes whereby to cause negative glow on the pairs of electrodes, and a shield interposed between one pair of the electrodes.

6. A negative glow device comprising an envelope having a gaseous filling of a substantially pure inert gas, said gas being under a pressure of between ten to twenty millimeters of mercury, a pair of spaced electrodes therein, means for connecting a source of alternating current across said electrodes to cause negative glow on both, and a shield interposed in the path of discharge between said electrodes, edges of said shield being extended beyond corresponding edges of one of said electrodes.

7. A negative glow device comprising an envelope having a gaseous filling of a substantially pure inert gas, said gas being under a pressure of approximately fifteen to twenty millimeters of mercury, a pair of spaced electrodes in said envelope, means for connecting a source of alternating current across said electrodes to cause negative glow on both, and a shield interposed in the path of discharge between said electrodes, said shield being of substantially greater area than one of said electrodes.
